J. G. BROWN.

TRACTION LUG.

APPLICATION FILED JULY 6, 1913.

1,077,667.

Patented Nov. 4, 1913.

UNITED STATES PATENT OFFICE.

J. GROVE BROWN, OF GROTON, NEW YORK, ASSIGNOR OF ONE-HALF TO GEORGE T. BACON, OF GROTON, NEW YORK.

TRACTION-LUG.

1,077,667.

Specification of Letters Patent.

Patented Nov. 4, 1913.

Application filed July 6, 1912. Serial No. 708,042.

To all whom it may concern:

Be it known that I, J. GROVE BROWN, a citizen of the United States, residing at Grotton, in the county of Tompkins and State of New York, have invented certain new and useful Improvements in Traction-Lugs, of which the following is a specification.

My invention relates to traction wheels, and more particularly to a removable lug 10 adapted to be secured to such wheels to prevent slipping.

While designed especially for use in connection with road engines or motor driven tractors, my invention is also applicable to 15 driving wheels of agricultural, excavating, or harvesting machinery.

The nature, objects, and advantages of the invention will fully appear from the following specification, reference being had 20 to the accompanying drawings forming a part thereof, and in which:—

Figure 1 is a side elevation of a complete wheel equipped with my improved traction lugs. Fig. 2 is an edge view thereof. Fig. 25 3 is a plan view, on an enlarged scale, of one of the lugs detached. Fig. 4 is a section taken on the line 4—4 of Fig. 3. Fig. 5 is a transverse section through the lug 30 on the line 5—5 of Fig. 3, the wheel rim being also shown, and Fig. 6 is a sectional view on the same scale, such section being taken on the line 6—6 of Fig. 2, looking in the direction of the arrow.

Referring to the drawings in detail, 1 35 designates a wheel rim to which are secured the usual spokes 2, terminating at the center in the hub 3. The rim 1 is preferably in the nature of a continuous flat band, as clearly shown in Figs. 5 and 6. To the 40 rim 1 are secured a series of my improved traction lugs designated in their entirety by the reference numeral 4, and held in position by means of central bolts 5, as hereinafter described.

45 Referring particularly to Fig. 3, it will be seen that my improved lug comprises a transverse rib 6, and a longitudinal rib 7, arranged substantially at right angles to each other, and connected at their point 50 of intersection by a circular boss 8. The ribs are also connected and braced by means of a comparatively thin web 9, which is adapted to lie snugly against the rim as shown in Fig. 6.

55 In the boss 8 is formed a countersunk

opening 10, adapted to receive the head of a bolt such as 5, and extending through the lug from the countersunk opening 10 is a hole 11, preferably made square, and adapted to receive a square shoulder on the 60 bolt, as indicated at 5^a, in Fig. 5. The shank of the bolt is circular as usual, and extends through a similar opening in the rim 1, the bolt and lug being held in place by the nut 15.

65 Referring again to Fig. 3, it will be seen that I provide interlocking means at the ends of the longitudinal rib of my improved lug. As shown in the drawings one end of this rib is bifurcated as indicated at 12, 70 and the walls of the bifurcated portion are preferably under-cut as indicated at 13, such under-cut walls being adapted to form a dove-tailed joint with the similarly shaped end 14 of the next adjacent lug.

75 It will be observed that but a single bolt is required to secure each lug in place, the lugs being held in position and prevented from becoming angularly displaced by virtue of the interlocking arrangement above 80 described. This single bolt feature very much simplifies the construction and facilitates removing and replacing the lugs as occasion may require. It will be further noted that the heads of the bolts 5 are 85 flush with the upper surface of the ribs and that the longitudinal ribs 7 abut so as to form a continuous circumferential fin, which serves to prevent side slipping. The lugs are each curved in the direction of the 90 length of the rib 7, as indicated in Fig. 4, so as to conform to the shape of the wheel, and it will therefore be seen, from an inspection of Figs. 1 and 2, that the ribs 7, 95 constitute a continuous unbroken smooth tread for the wheel. This is very desirable to prevent excessive jolting when the wheel rolls upon a hard surface into which the ribs cannot bite, as for example a pavement.

100 It will be thus seen that I have provided a readily detachable traction lug which affords an effective gripping action both against slipping and against side thrust, and at the same time constitutes a smooth rolling surface or tread for use on hard roads, 105 and it is thought that the many advantages of my invention will be readily appreciated without further discussion.

What I claim is:—

1. A removable traction lug comprising a 110

2
web, a central boss projecting outwardly therefrom, said boss having an opening transformed therein, and longitudinal and transverse ribs radiating from said boss and projecting outwardly from said web.

5. 2. A removable traction lug comprising a web, a central boss and longitudinal and transverse ribs all projecting outwardly from said web, and all being of the same height, said boss having a bolt hole extending therethrough, the outer end of said hole being countersunk.

10. 3. A traction lug comprising a web, longitudinal and transverse ribs projecting outwardly from said web, one end of said longitudinal rib being bifurcated, and the other end being formed to fit such bifurcation, the construction being such that two similar lugs are adapted to interlock, when 15 placed end to end, and each lug being pro-

vided with but a single fastening device, whereby it may be individually secured upon a wheel.

4. The combination with the rim of a traction wheel, of a series of removable lugs 25 independently secured thereto, each lug comprising transverse and longitudinal ribs disposed substantially at right angles to each other and projecting radially beyond the wheel rim, said longitudinal ribs being 30 constructed to interlock and placed end to end to form a continuous smooth circumferential fin or tread.

In testimony whereof I affix my signature, in presence of two witnesses.

J. GROVE BROWN.

Witnesses:

B. L. BUCK,
W. E. GABEL.
